UNITED STATES PATENT OFFICE.

CHARLES SEYMOUR, OF DEFIANCE, OHIO, ASSIGNOR TO DEFIANCE MACHINE WORKS, OF DEFIANCE, OHIO.

HYDRAULIC PRESS.

SPECIFICATION forming part of Letters Patent No. 728,628, dated May 19, 1903.

Application filed November 19, 1902. Serial No. 131,986. (No model.)

To all whom it may concern:

Be it known that I, CHARLES SEYMOUR, a citizen of the United States, and a resident of Defiance, in the county of Defiance and State 5 of Ohio, have invented a new and Improved Hydraulic Press, of which the following is a full, clear, and exact description.

The object of the invention is to provide a new and improved hydraulic press which is 10 simple and durable in construction, very effective in operation, completely under the control of the operator to permit instant regulation of the pressure to be exerted, and more especially designed for pressing axle-boxes 15 upon the hubs of wheels, for pressing bands and flanges upon the wheel-hubs, and for various other purposes.

The invention consists of novel features 20 and parts and combinations of the same, as will be more fully described hereinafter and then pointed out in the claims.

A practical embodiment of the invention is 25 represented in the accompanying drawings, forming a part of this specification, in which similar characters of reference indicate corresponding parts in all the views.

Figure 1 is a perspective view of the improvement as applied for pressing the band onto the hub of a wheel. Fig. 2 is an enlarged 30 sectional side elevation of the double-acting pump, the section being on the line 2 2 of Fig. 4. Fig. 3 is a similar view of the same on the line 3 3 of Fig. 4. Fig. 4 is a sectional plan view of the same on the line 4 4 of Fig. 35. Fig. 5 is an enlarged sectional plan view of the same on the line 5 5 of Fig. 3. Fig. 6 is an enlarged transverse section of the same on the line 6 6 of Fig. 4; and Fig. 7 is an enlarged sectional side elevation of the safety 40 valve, the section being on the line 7 7 of Fig. 4.

The main frame of the hydraulic press shown in Fig. 1 consists of suitable standards A and A', connected with each other by a base-beam B and a top beam B', of which the latter carries on its under side an adjusting-screw C, and the base-beam B supports on its top a hydraulic cylinder D, in which operates a piston D', extending upwardly through 45 the top of the cylinder in axial alinement with the adjusting-screw C. The work E is placed

between a piston-head D³ and the adjusting-screw C in the usual manner.

The lower end of the cylinder D is connected by a pipe D² with a reservoir F, arranged within a casing G, held on the main frame of the press, and this casing is adapted to contain water, oil, or other suitable liquid. 55

The reservoir F forms part of a double-acting pump arranged horizontally and submerged in the liquid contained in the casing G, and the said pump is constructed in detail as follows: Horizontal cylinders H and H' in axial alinement with each other are provided at their outer ends with valved suction I and I', opening into the liquid contained in the casing G, and the said cylinders are connected by valved outlets J and J' with the reservoir F, so that when the double-acting pump is in motion the liquid is sucked in 60 from the casing G by way of the suctions I and I' into the cylinders H and H', to be discharged from the latter through the outlets J and J' into the reservoir F, from which the liquid passes under pressure through the pipe 65 D² into the hydraulic cylinder D to force the piston D' therein upward for exerting the desired pressure on the work. 70

The valves of the suctions I and I' and outlets J and J' are preferably in the form of 75 ball-valves normally held to their seats by springs, as plainly shown in Fig. 5. In the cylinders H and H' reciprocate plungers H² and H³, secured at their inner ends on a cross-head K, mounted to slide longitudinally on 80 guideways G', formed in the bottom of the casing G, and in the said cross-head K is formed a vertical guideway K' for a trunnion-block K² to slide in, the said block being pivotally connected at its trunnion with one arm 85 L' of a double or bell-crank lever L, having its pivot L² mounted to turn in suitable bearings formed in the front and rear sides of the casing G. (See Fig. 4.) The other arm L³ of the bell-crank lever L is pivotally connected by a pitman N with the crank-arm O of a main shaft O', journaled on the top of the top cross-beam B', as plainly indicated in Fig. 1, and on the said main shaft are arranged fast and loose pulleys P, connected by a belt 90 with other machinery for imparting a rotary motion to the main shaft O'. A shifting-

lever P' under the control of the operator serves to control the belt for the pulleys P.

Now when the main shaft O' rotates its crank-arm O imparts motion to the pitman N 5 to rock the bell-crank lever L, so that the latter by the block K² imparts a reciprocating motion to the cross-head K for actuating the plungers H² and H³ in the cylinders H and H' to cause alternate suction and discharge of 10 the liquid from the casing G into the reservoir F, as above described.

The pitman N extends loosely through a large opening G² in the top of the casing G, and in order to prevent dust and other impurities from passing into the casing G and 15 to the liquid contained therein a stuffing-box Q is provided arranged on the top of the casing G, as plainly indicated in Figs. 1, 2, and 3. The stuffing-box Q is made flexible, so as 20 to conform to the swinging motion of the pitman N, and for this purpose the said stuffing-box is provided with a tube Q' in the shape of the frustum of a cone and made of leather, rubber, or similar flexible material. Into the 25 ends of the tube Q' are fitted metallic rings Q² Q³, of which the ring Q³ in the apex end of the tube Q' fits snugly around the pitman N, while the lower or base ring Q² is sufficiently large to allow free movement of the 30 pitman through the said ring. Clamping-rings Q⁴ and Q⁵ engage the ends of the tube Q' at the outside thereof to securely fasten the several parts together, the ring Q⁴ being preferably flanged and secured by bolts Q⁶ to 35 the top of the casing.

Now it is evident that when the machine is in motion and the pitman N rocks the tube Q' readily swings with the pitman owing to the flexible nature of the tube Q'.

40 The reservoir F is provided with a discharge R, opening into the casing G and having a plug-valve R', (see Fig. 6,) engaged by a stem R², extending upwardly through a suitable stuffing-box R³, secured to the top of 45 the casing G, and on the outer end of the said stem R² is arranged a handle R⁴, under the control of the operator, for opening or closing the plug-valve R' to connect or disconnect the reservoir F and the interior of the casing G.

Now by the arrangement described the pressure-supply to the pipe D² and hydraulic cylinder D can be instantly stopped by the operator opening the plug-valve R' without 55 stopping the pump, and by opening the plug-valve R' more or less more or less pressure can be supplied to the pipe D² and the cylinder D. The reservoir F is also provided with a safety-valve S, (see Figs. 2 and 7,) and for 60 this purpose the reservoir F is provided with a branch pipe F', into which screws the casing S' of the safety-valve, the said casing being provided with a ball-valve S², controlling the connection between the branch pipe F' 65 and the outlets S³, formed in the casing S' and opening into the casing G. On the top of the ball-valve S² rests a plug S⁴, mounted

to slide in the casing S' and engaged on its top by one end of a lever S⁵, fulcrumed on the casing S'. A spring S⁶ is connected with 70 the outer end of the lever S⁵ and is attached to a screw-rod S⁷, extending upwardly through a cap S⁸ to be engaged at its outer end by nuts S⁹, which serve to regulate the tension of the spring S⁶ to allow of setting the safety- 75 valve to any desired pressure.

Now it is understood that when the press is in operation and the pressure exerted against the piston D' in the cylinder D exceeds the pressure to which the safety-valve S is set 80 then the liquid forces the valve S² upward into an open position to allow the liquid to pass from the reservoir F by way of the branch pipe F' and openings S³ back into the casing G. From the top of the reservoir F leads a 85 pressure-gage pipe T' to a pressure-gage T for indicating the pressure within the reservoir F, and consequently that exerted against the piston D'. The top of the casing G is provided with a filling-plug U to fill the casing G with the desired amount of liquid.

The operation is as follows: The work E is placed in position between the head D⁸ of the piston D' and the adjusting-screw C, and then the operator shifts the shifting-lever P' to 95 move the belt from the loose to the fast pulley P to rotate the shaft O', whereby a reciprocating motion is given to the cross-head K by the intermediate mechanism above described. The plungers H² and H³, carried by 100 the cross-head K, now cause alternate suction and discharge of the liquid from the casing G into the reservoir F, from which the liquid passes by the pipe D² into the cylinder D to force the piston D' therein upward to 105 subject the work E to the desired pressure, and when the work is finished the operator turns the handle R⁴, so that the plug-valve R' moves into an open position to cause the liquid to discharge from the reservoir F back into the 110 casing G without stopping the action of the main shaft O'. The piston D' is thus relieved of pressure and readily returns to a lowermost position to allow removal of the finished work and placing of new work in position on the head D⁸, after which the handle R⁴ is turned to its former position to close the 115 plug-valve R', so that the pressure of the pump is again exerted against the piston D', and the above-described operation is repeated. 120 Thus by the arrangement described the double-acting pump need not be stopped while removing the finished work and placing new work in position, it being only necessary for the operator to manipulate the handle R⁴ as 125 above explained.

As the double-acting pump is disposed horizontally within the casing and practically submerged in the liquid contained in the casing, there is no danger of the pump working dry, as the liquid by its own gravity, besides the suction action of the pistons, readily fills the cylinders, so that no air-pockets are liable 130 to form in the cylinders, reservoir F, pipe D²,

or hydraulic cylinder D, and hence a positive and direct action of the piston D' is always the result.

The double-acting pump and parts connected therewith are very simple in construction and not liable to get out of order.

Having thus described my invention, I claim as new and desire to secure by Letters Patent—

- 10 1. A hydraulic press provided with a double-acting pump, comprising a casing for containing a liquid, a lined horizontally-disposed pump - cylinders within the casing, having valved suction and valved discharges, plungers in the said cylinders, a cross-head mounted to slide in the casing and carrying the said plungers, a double crank-arm mounted to rock in the casing and having one arm connected with the cross-head, a pitman connected 15 with the other arm of the crank-arm, a revolute crank-shaft outside the casing, connected with the said pitman, and a flexible stuffing-box on the said casing, through which passes the said pitman, as set forth.
- 20 2. A hydraulic press having a casing for containing a liquid, a pump within the casing, a double crank-arm for actuating the pump, a pitman connected with the double

crank-arm and extending through an opening in the casing, a crank-shaft connected 30 with the pitman, and a flexible stuffing-box for the pitman, secured to the casing, as set forth.

3. A stuffing-box for an oscillating part, comprising a flexible tube, rings fitting the 35 inside of the tube, one of the rings fitting the said part slidably, and means for clamping the outside of the tube at the rings, one of the means being fixed, as set forth.

4. A stuffing-box for a pitman, extending 40 loosely through an opening in a casing, comprising a tube in the shape of the frustum of a cone, rings inserted in the ends of the tube, the ring in the apex end of the tube slidably fitting the pitman, a clamping-ring 45 outside of the apex end of the cone, and a fastening-ring on the outside of the base end of the tube, secured to the said casing, as set forth.

In testimony whereof I have signed my 50 name to this specification in the presence of two subscribing witnesses.

CHARLES SEYMOUR.
